(57) **CLAIM**

The ornamental design for a “refrigerator/freezer,” as shown and described.

DESCRIPTION

FIG. 1 is a front, right perspective view of a “refrigerator/freezer” showing my new design;

FIG. 2 is a front elevational view thereof;

FIG. 3 is a bottom plan view thereof;

FIG. 4 is a top plan view thereof;

FIG. 5 is a right elevational view thereof, the left side elevational being a mirror image thereto;

FIG. 6 is a rear elevational view thereof; and,

FIG. 7 is an enlarged front perspective view of FIG. 2, shown with the doors opened.
